ELECTRIC VALVE CONTROL SYSTEM

Emil M. Kaegi, deceased, late of Wauwatosa, Wis.,
by Anna E. Kaegi, special administratrix, Wau-
watosa, Wis., assignor to Allis-Chalmers Manu-
facturing Company, Milwaukee, Wis., a cor-
poration of Delaware

Application April 21, 1937, Serial No. 138,189

2 Claims. (Cl. 250—41.5)

This invention relates in general to improvements in electric valve control systems, and more particularly to means for controlling the operation of an electric valve controlling the flow of current in a circuit operating at such high voltage as to render the insulation of control apparatus associated with the valve difficult and expensive.

Electric valves are frequently utilized for controlling the flow of current in circuits at high voltages, one example of such use being the rectification of current at a voltage of several thousand volts for supplying radio broadcasting transmitters. It has also been proposed to utilize electric valves for rectifying current to be transmitted at high voltage between a generating station and a substation distant therefrom, and also for converting the direct current to alternating current at such distant substation. Such valves generally require, for the control thereof, a large number of supervisory and protective devices which are connected with the main high voltage circuit controlled by the valve and with an auxiliary circuit of such low voltage as to be without danger for the operators who may come into accidental contact therewith. Such devices must therefore be insulated for the full voltage of the main circuit to ground, or else the circuits of such devices must include insulating transformers likewise insulated for the full main circuit voltage to ground. Such insulation is frequently difficult to provide and always adds considerably to the cost of the installation.

It is therefore more advantageous to separate each control device into two portions having no physical contact with each other and to transmit control impulses from one portion to the other of the device by means of electromagnetic or other waves. Although waves of any frequency may be utilized, such as the so-called infra-red, ultra-violet, radio waves, or sound waves, it is generally more convenient to utilize light waves produced in one portion of the control device and focused on a light sensitive device forming part of the other portion. More particularly, it is preferable to utilize electric light sources which are caused to receive current only when a control impulse is to be transmitted so as to lengthen the life of the light sources utilized.

It is therefore one of the objects of the present invention to provide an electric valve control system in which control impulses are transmitted between an intermittently operating source of electromagnetic or other waves and a device sensitive to such waves.

Another object of the present invention is to provide an electric valve control system in which control impulses are transmitted between an intermittently operating source of light and a light sensitive device.

Another object of the present invention is to provide an electric valve control system in which a plurality of different control operations utilize control impulses transmitted between a common source of light and a common light sensitive device.

Objects and advantages other than those above set forth will be apparent from the following description when read in connection with the accompanying drawings, in which:

Fig. 1 and Fig. 1a together diagrammatically illustrate an electric valve converting system in which different control operations are effected by means of control impulses transmitted between light sources and light sensitive devices;

Fig. 2 diagrammatically illustrates the relationship between the coils and the contacts of some of the relays utilized in the system illustrated in Figs. 1 and 1a;

Fig. 3 diagrammatically illustrates the arrangement and the connections of any one of the electronic relays utilized in the system illustrated in Figs. 1 and 1a; and

Fig. 4 illustrates one example of a physical arrangement of the system illustrated in Figs. 1 and 1a.

Referring more particularly to the drawings by characters of reference, reference numeral 6 designates an alternating current line or circuit connected with a suitable generator (not shown) and serving as a source of electric current for a main electric circuit 1. Circuits 6 and 1 are connected by means of a switch 8, a transformer 9 having a primary winding 11 and a secondary winding 12, and one or more electric valves 13. Circuit 6 also supplies current to an auxiliary transformer 14 having the secondary winding thereof connected with a grounded auxiliary circuit 16 for the control of valves 13. Circuit 16 is thus insulated from circuit 1 by means of transformers 9 and 14 and operates at such low voltage as to be without danger for the operators in charge of the system. Circuit 6 is also connected through a switch 17 with the primary winding of a transformer 18 supplying current to a second auxiliary circuit 19 having a plurality of phase conductors and having a neutral conductor connected with one of the conductors of circuit 7.

Valves 13 are provided for rectifying current

supplied thereto from winding 12 and to thereby control the flow of current through circuit 7. Such valves may be of any type known in the art and are herein assumed to be of the discontinuously controllable or vapor type each having an anode 21. The anodes of the different valves are preferably arranged within a common casting, the cathodes of the valves then being combined to form a single cathode structure 22 connected with one of the conductors of circuit 7 and with the neutral conductor of circuit 19.

The operation of valves 13 is controlled by a plurality of control means each connected with one of circuits 7 and 16 and each comprising a device sensitive to electromagnetic or other waves such as a light sensitive device. A suitable source of electromagnetic or other waves such as an electric light source is arranged to illuminate the light sensitive device and is associated with suitable means connected with the other one of circuits 7 and 16 for controlling the supply of current to the light source for the purpose of operating the associated control means. More particularly, means connected with circuit 7 are provided for controlling the conductivity of valves 13 by establishing and maintaining an electron emission at cathode 22. Such means comprise an ignition anode 23 suspended from a spring 24 and provided with an armature 26. A solenoid 27 cooperates with armature 26 to cause operation of the ignition anode. The ignition anode is connected with the secondary winding of a transformer 28 through spring 24, a resistor 29, contact 31a of a relay 31 and contact 32a of a relay 32. Solenoid 27 is connected between the secondary winding terminals of transformer 28 through contact 33a of a relay 33 and through contact 32b of relay 32. The secondary winding neutral point of transformer 28 is connected with cathode 22 through the coils of relays 31 and 33 and through a reactor 34 connected in parallel with a second reactor 36 through contact 31b of relay 31. The secondary winding terminals of transformer 28 are also connected with a pair of excitation anodes 30 of valves 13 through a pair of resistors 35.

The coil of relay 32 is connected with circuit 19 through an electronic relay generally designated by 37 and controlled by a light sensitive device 38. Device 38 may be of any suitable known type such as the so-called selenium cells and photo voltaic cells, but is preferably of the type known as a phototube. Such phototube comprises essentially a glass bulb containing two electrodes separated by a space having a conductivity depending on the degree of illumination of the bulb. Relay 37 may be of any known type adapted to be controlled by phototube 38. One example of such type of relay is diagrammatically illustrated in Fig. 3, which may be assumed to be representative of all the electronic relays utilized in the system illustrated in Fig. 1. Such relay comprises a transformer 39 which, in the present instance, is energized from circuit 19, but which may be energized from circuit 16 when the device to be controlled thereby is connected with the low voltage portion of the system. The coil of relay 32 is connected between one terminal and an intermediate tap of the secondary winding of transformer 39 through a valve 41 of the three electrode high vacuum type. Phototube 38 is connected between the anode and the grid of valve 41 and a capacitor 42 is connected between the grid of the valve and the other secondary terminal of transformer 39. A capacitor 43 is pref-

erably connected in parallel with the coil of relay 32 to render the flow of current therethrough more uniform.

A suitable source of light such as an electric lamp 44 is arranged to illuminate phototube 38. Lamp 44 is preferably of the incandescent type and is provided with suitable means connected with circuit 16 such as a push button switch 46 for controlling the supply of current from circuit 16 to the filament of the lamp to cause operation of relay 32. The light produced by lamp 44 may be focused on phototube 38 by means of a lens 47 or of an equivalent optical system, and phototube 38 may be shielded against light emitted by sources other than lamp 44 by means of a hood 48. The primary winding of transformer 28 may be connected across two conductors of circuit 19 through contact 49a of a relay 49. Relay 49 is caused to operate similarly to relay 32 by means of an electronic relay 51 similar to relay 37, a phototube 52, a lamp 53 and a switch 54 for connecting the filament of lamp 53 with circuit 16. If desired relay 49 may be provided with a holding coil connected with circuit 19 by means of a second contact 49b of relay 49.

The conductivity of valves 13 may be further controlled by additional means which are also connected with circuit 7 and controlled by means of light sources energized from circuit 16. Such means comprise a plurality of control electrodes 56 severally associated with anodes 21 and serving to control the moments of initiation of the periods of current flow through each anode. Such moments are determined by the impression on each control electrode of potential varying from a negative value to a positive value relative to the potential of cathode 22 taken as datum for control potentials. Each control electrode is accordingly connected through a current limiting resistor 57 with one of the phase portions of the secondary winding 58 of a control transformer 59 having a primary winding 61. Winding 61 is connected with circuit 19 through a plurality of current limiting resistors 62 and through the coils of three relays 63, 64 and 66. Relays 63, 64 are provided for additionally controlling the conductivity of valves 13 and operate responsive to an abnormal operating condition of the valves for rendering the valves non-conductive. Relay 66 is of the lockout type operable to close a contact controlling the supply of current to a light source only after a predetermined number of operations of relays 63 and 64. Relay 63 is a fast acting relay provided with contacts 63a, 63b arranged to short circuit the different portions of winding 61. One of resistors 62 is connected in parallel with a circuit comprising the serial arrangement of an indicating device 67, contact 64a of relay 64, and the coil of another relay 69. The coil of relay 63 is connected with the secondary winding of a current transformer 71 having the primary winding thereof energized from a current transformer 72 connected between circuit 6 and switch 8. The secondary circuit of current transformer 72 is preferably grounded, and current transformer 71 serves to insulate such circuit from circuits 19 and 7.

Current transformer 72 and two other current transformers 73 and 74 in the connections between circuit 6 and switch 8 supply current to the coils of three relatively slowly acting overload relays 76, 77, 78. The coil of relay 76 is bridged by a resistor 79 and contact 81a of a relay 81. The coil of relay 77 is bridged by another 75

resistor 82 and contact 81b of relay 81. The coil of relay 78 is connected in series with the coil of relay 81 connected in parallel with a resistor 83 through contact 81c of relay 81. Relays 16, 57, 78 are provided with contacts 16a, 71a, 18a connected in parallel and operable to short circuit the holding coil 8a of switch 8 through an indicating device 84 and through contacts 8b of switch 8. When switch 8 is closed, holding coil 16a is normally supplied with current from circuit 16 through a resistor 86, a push button switch 87 and contacts 8b to maintain latch 8c of switch 8 in the operative position thereof.

The secondary winding 58 of transformer 59 is connected in star to form a neutral point connected with cathode 22 through a capacitor 88 and through the taps of two rheostats 89 and 91. Rheostat 89 is associated with two resistors 92 and 93 to form a voltage divider receiving current from a direct current generator 94. Rheostat 91 is associated with two other resistors 96 and 97 to form a second voltage divider also receiving current from generator 94. Generator 94 is driven by a motor 98 connected with circuit 19 through a switch 99. Switch 99 is controlled by an electronic relay 101 connected with a phototube 102. The operation of relay 101 is controlled by a lamp 103 receiving current from circuit 16 through a switch 104. The taps of rheostats 89 and 91 are movable for impressing a variable potential from generator 94 on control electrodes 56 to control the operation of valves 13. For controlling the operation of such potential impressing means, the taps are jointly actuated by a reversible electric motor 106 of any suitable known type. Motor 106 is assumed to have a squirrel cage armature and an exciting winding energized from circuit 19, and to be provided with a pair of shading coils severally adapted to be short circuited by means of relays 107 and 108. Such action of the relays may be controlled by suitable limit switches such as at 110. Relay 107 is controlled by a relay 109 connected with a phototube 111 cooperating with a lamp 112 connected with circuit 16 through a switch 113. Relay 108 is controlled by a relay 114 connected with a phototube 116 cooperating with a lamp 117 connected with circuit 16 through a switch 118. The neutral point of winding 58 may also be connected with cathode 22 through generator 94 upon operation of contacts 63c, 63d, 63e, 63f of relay 63 or of contacts 63c, 63d, 63e and 63f of relay 63.

Valves 13 are generally provided with means for controlling the vapor pressure within the casing thereof. Such means comprise a pump 119 of the so-called diffusion type comprising an electric heater element 120 connected with circuit 19 through the contact of a relay 121 and through the coil of a relay 122. Relay 121 is controlled by a relay 123 connected with a phototube 124 cooperating with a lamp 126 connected with circuit 16 through a switch 127. Pump 119 is preferably provided with a water jacket having suitable cooling means such as a radiator 128. Pump 119 discharges into another pump 129 of the sliding vane type driven by a motor 131. Motor 131 is connected with circuit 19 through a switch 132 controlled by a relay 133 connected with a phototube 134. The phototube cooperates with a lamp 136 connected with circuit 16 through a switch 137.

The control system comprises a plurality of means connected with circuits 7 and 19 and each responsive to an operating condition of valves 13 for momentarily supplying electric current

or otherwise controlling the supply of current to a light source to cause operation of suitable controlling means for the valves such as switch 8 or of other means for causing interruption of the flow of current through the valves. The responsive means include relay 66 operable in dependence upon the flow of current through the portion of circuit 19 connected with the coil of the relay and having a contact 66a for connecting a lamp 138 with circuit 19. Lamp 138 10 cooperates with a phototube 139 connected with a relay 141 controlling a relay 142. Contact 142a of relay 142 is operable to short circuit holding coil 8a and contact 8b of switch 8 through an indicating device 143 for causing opening of 15 switch 8 and interruption of the flow of current through valves 13. Relay 142 responsive to the flow of current through heater 120 is provided with a contact 142a for connecting lamp 138 with circuit 19 through an indicating device 144.

Valves 13 are also provided with means connected with circuit 7 and responsive to an operating condition other than an electrical condition of valves 13 for controlling the supply 25 of current to lamp 138. Such means comprise means responsive to a physical condition of the operating vapor within valves 13 such as the temperature or the pressure thereof. The temperature responsive means comprise a temperature 30 responsive device 146 having a contact 146a operable to connect lamp 138 with circuit 19 through an indicating device 147. The pressure responsive means comprise a resistor 148 in contact with the operating vapor within the valve and 35 forming part of a resistance bridge 149. The bridge receives rectified current from circuit 19 through a rectifier 151, and the flow of such current through the bridge is affected by the changes in the resistance value of resistor 148 40 in response to the variation of temperature thereof resulting from variations of the vapor pressure thereabout. The output terminals of bridge 148 are connected to an indicating device 152 and to a relay 153 having a contact 153a operable to connect lamp 138 with circuit 19 through an indicating device 154. A second temperature responsive device 156 mounted on the water 45 circulating system of pump 119 is provided with a contact 156a adapted to connect lamp 138 with circuit 19 through an indicating device 157.

To prevent continuous operation of valves 13 when one or more of the conductors of circuit 19 accidentally become deenergized, three lamps 158 are permanently connected between the different conductors of circuit 19 and are arranged to illuminate a single phototube 159. Phototube 159 is connected with a relay 161 controlling a relay 162 having a contact 162a for short circuiting holding coil 8a through an indicating device 163. Phototube 159 is selected of such characteristic as to cause operation of relay 162 if one or more of lamps 158 cease to operate.

Fig. 4 illustrates one manner of arranging the equipment diagrammatically illustrated in Figs. 1, 1a, 2 and 3. Valves 13, the associated mechanical equipment and the different devices connected with circuit 19 are mounted on a platform supported on insulators 166. The apparatus connected with circuit 16 and with current transformers 72, 73, 74 are mounted on a switchboard 167 separated from the high voltage equipment by a fence 168.

The operation of the system will be considered assuming that circuit 6 is energized from the generator connected therewith and that the different 75

elements of the system are in the position shown in the drawings. It will be understood however that the system may also be utilized when valves 13 are used for converting direct current supplied to circuit 7 by a suitable generator into alternating current to be supplied to circuit 6. When it is desired to put valves 13 in operation, switch 17 is closed to energize circuit 19, thus causing lamps 158 to receive current. If all three conductors of circuit 19 are normally energized, phototube 159 receives an amount of light from the lamps sufficient to cause operation of relay 162. Such operation will be considered somewhat in detail assuming that relay 161 is of the type represented in Fig. 3. As long as lamps 158 remain dark phototube 159 is substantially non-conductive. The associated transformer 39 then charges capacitor 42 through the cathode of the associated valve 41 and through the grid of the valve acting 20 as an anode. The charge taken by the capacitor is such that the grid of the valve is at a variable negative potential with respect to the potential of the cathode of valve 41 at least when the associated anode is at a positive potential with respect to the cathode potential. Valve 41 is then substantially non-conductive for the flow of current between the anode and the cathode thereof. When lamps 158 receive current and illuminate phototube 159, the phototube becomes materially 30 conductive and connects the grid of valve 41 with the anode thereof. Capacitor 42 discharges and the grid of valve 41 may reach a positive potential with respect to the potential of the cathode when the associated anode is likewise at a positive 35 potential. The valve is then conductive, and a pulsating current is transmitted from transformer 39 through the coil of relay 162 and through valve 41. The flow of current through the coil is rendered substantially uniform by 40 means of capacitor 43. The above described method of operation is characteristic of all the electronic relays utilized in the system and will therefore not be repeated in connection with the description of the operation of each individual 45 relay.

Relay 162 operates upon energization of the coil thereof to open contact 162a in circuit with the holding coil 8a of switch 8 to permit subsequent closure of the switch. Switch 127 is then 50 closed to supply current to lamp 126 and the lamp illuminates phototube 124. As a result thereof relay 123 causes relay 121 to complete the circuit of heater 120. Switch 137 may also be closed to supply current to lamp 136. The lamp illuminates 55 phototube 134 to cause relay 132 to connect motor 131 with circuit 16. Motor 131 thereupon starts pump 129 and maintains such pump in continuous operation. Switches 127 and 137 must, however, remain closed unless relays 121 and 132 are 60 provided with holding coils.

When the vapor pressure within valves 13 has been lowered to the required extent by operation of the pumps, switch 54 may be closed to supply current to lamp 53 which thereupon illuminates 65 phototube 52. Such operation causes relay 49 to operate to connect transformer 28 across two conductors of circuit 19. If relay 49 is provided with a holding coil, switch 54 may then be opened and relay 49 will remain in the energized position until switch 17 is opened. Push button 46 70 may then be actuated to supply current to lamp 44 through contact 46a. At the same time contact 46b short circuits holding coil 8a of switch 8 to cause opening of the switch if it has been inadvertently closed. Lamp 44 illuminates photo-

cell 38 with the result that relay 32 closes the contacts thereof. Contacts 32b and 33a connect solenoid 27 across the secondary winding of transformer 28 and the solenoid accordingly urges armature 26 downward to cause ignition anode 23 to come in contact with cathode 22. Contact 32a completes a circuit from the secondary winding of transformer 28 through contacts 32a, 31a, resistor 29, spring 24, ignition anode 23, cathode 22, the coils of relays 31 and 33, reactor 34 and reactor 36 10 and contact 31b back to the transformer. Relay 33 operates in response to the flow of current through such circuit to open contact 33a in the solenoid circuit. The solenoid is therefore de-energized, spring 24 then returns ignition anode 15 23 to the position shown and an arc is drawn between ignition anode 23 and cathode 22.

An electron emission is thus established at the cathode and current may flow alternately from the two excitation anodes 30 to cathode 22 to 20 maintain the cathode continuously in electron emitting condition. Such current is rectified at cathode 22 and flows to the neutral point of the secondary winding of transformer 28 by way of the coils of relays 31 and 33 and of reactors 34 25 and 36. Relay 31 thereupon operates to open contacts 31a and 31b to thereby disconnect ignition anode 23 and reactor 36 from the circuit. Push button switch 46 may then be released, thereby causing relay 32 to return to the position 30 shown. Contact 46b is also opened to permit subsequent closure of switch 8.

Switch 104 is thereafter closed to supply current to lamp 103. Phototube 102 is illuminated by the lamp and causes switch 99 to connect motor 35 38 with circuit 19. Motor 38 accordingly starts and drives generator 34 which supplies direct current to voltage dividers 92, 89, 93 and 96, 91, 97. Switch 118 is then closed momentarily to supply current to lamp 117 to cause operation of relay 40 108. Such relay short circuits the shading coil on the right hand side of motor 106. Motor 106 accordingly rotates until opening of limit switch 110 to actuate the tap of rheostats 89 and 91 in such manner as to impress a maximum negative 45 potential on the neutral point of winding 58. Each control electrode 56 of valves 13 is then subjected to an alternating potential from winding 58 superposed on a maximum negative potential received from generator 34 through the voltage dividers. Switch 8 may then be closed and the switch is maintained closed by means of latch 8c thereof which is urged in latching position by coil 8a energized from circuit 16 through resistor 8b, push button switch 87 and contact 8b. 50

Upon closure of the switch the different anodes 21 are brought sequentially to a positive potential with respect to the potential of cathode 22. By reason of the adjustment of rheostats 89 and 91, the control electrode 56 associated with 60 each anode 21 becomes positive with respect to the potential of cathode 22 to release the flow of current through the associated anode at moments of the voltage cycle of circuit 6 when the associated anode has a potential of relatively low 65 value. The output voltage of the system impressed on circuit 7 is then of relatively low value as is well known. Switch 113 may then be closed for a suitable period of time to supply current to lamp 112. Relay 107 is thus caused to operate and to short circuit the shading coil on the left hand side of motor 106. Motor 106 is thus caused to rotate in a direction opposite to the direction of rotation previously considered. The adjustment of rheostats 89 and 91 is thus gradu- 70 75 75

ally varied to decrease the unidirectional potential component impressed on the control electrodes 56 through the voltage dividers. Each control electrode then becomes positive with respect to cathode 22 at an earlier moment of the voltage cycle of circuit 6. The output voltage of valves 13 is accordingly gradually increased as is well known and switch 113 may be opened to cause motor 106 to stop when the voltage of circuit 7 has reached the desired value. Such voltage may also be adjusted from time to time by varying the adjustment of rheostats 89 and 91 to regulate the flow of current through valves 13. Such adjustment may also be effected automatically in response to an operating condition of valves 13 such as the voltage of circuit 7 or the magnitude of the flow of current therethrough as is well known.

During such operation current transformers 20 72, 73, 74 supply currents to relays 76, 77, 78 and 63 which are of insufficient value to cause operation of the relays. Upon occurrence of an abnormal condition in the operation of the system causing a flow of current of excessive value 25 through valves 13, current transformer 72 acting through current transformer 71 supplies the coil of relay 63 with current of sufficient magnitude to cause the relay to operate. Relay 63 short circuits winding 61 by means of contacts 63a, 63b. Relay 63 also connects the neutral point of winding 58 with cathode 22 through generator 94 by means of contacts 63d, 63f and disconnects the voltage dividers by means of contacts 63c, 63e. The control electrodes of valves 13 are thus maintained continuously at a negative potential with respect to the potential of cathode 22 and the flow of current through valves 13 is thereby caused to cease as is well known.

Closure of contacts 63a, 63b causes circuit 19 40 to supply current to the coils of relays 63, 64 and 66 of sufficient magnitude to maintain relay 63 energized after interruption of the flow of current through valves 13 and to cause relay 64 to operate to close contact 64a after a time 45 delay. The coil of relay 69 is energized through contact 64a and relay 69 actuates contacts 69a to 69f thereof to relieve the contacts of relay 63 from further duty. Contact 69a also short circuits the coil of relay 63, which returns to the position 50 shown, and contact 69b short circuits the coil of relay 64, which opens contact 64a. Relay 69 then also returns to the position shown and the flow of current through valves 13 is reestablished. Such 55 operation of the relays is indicated by means of indicator 67 and is also registered temporarily by relay 66. If the abnormal operating condition of the system is such that the current therethrough again reaches an excessive value upon being reestablished, the above sequence of operation 60 is repeated for rendering valves 13 non-conductive. Upon repetition of such sequence of operation a predetermined number of times within a predetermined time period, relay 66 closes contact 66a, thereby causing lamp 138 to receive current from circuit 19. Lamp 138 illuminates phototube 158 and causes operation of relay 142. Relay 142 closes contact 142a, thus short circuiting holding coil 8a of switch 8 through contact 8b and through indicating device 143. 65 Latch 8c of switch 8 is thereby released and the switch opens.

If after one cycle of operation of relays 63, 64, 66 and 69 the flow of current through valves 13 is not completely interrupted for any reason such as faulty operation of control electrodes 56,

relay 63 remains energized from current transformer 72 through current transformer 71 and the relay maintains the contacts thereof closed even after operation of relay 69. The coil of relay 81 also remains energized and relay 81 5 operates to open contacts 81a, 81b, 81c. The coil of relay 76 thereupon receives the full current of current transformer 74 and the coil of relay 77 receives the full current of current transformer 73 and at least one of such relays operates 10 to close contacts 76a or 77a, thus causing tripping of switch 8. If relay 63 fails completely to operate, the coils of relays 76, 77, 78 receive sufficient current from current transformers 72, 73, 74 for a sufficient length of time to cause operation 15 of the relays and resulting opening of switch 8.

Switch 8 is also caused to open in dependence upon the flow of current through different portions of auxiliary circuit 19 by means other than relay 66 comprising relay 122 and lamps 158. If 20 at least one of lamps 158 ceases to operate, phototube 158 loses sufficient conductivity to cause relay 142 to operate to close contact 142a to thereby cause switch 8 to be opened. If the flow of current through heater 120 fails, relay 25 122 closes contact 122a which connects lamp 138 with circuit 19 through indicator 144.

If the temperature of the operating vapor within valve 13 becomes excessively high, device 146 closes contact 146a connecting lamp 138 with 30 circuit 19 through indicator 147. If the temperature of the water jacket of pump 119 becomes excessively high, device 156 closes contact 156a connecting lamp 138 with circuit 19 through indicating device 157. If the pressure of the 35 vapor within valves 13 becomes excessively high, the balance of bridge 149 is affected in such manner that relay 153 operates to close contact 153a connecting lamp 138 with circuit 19 through indicator 154. When lamp 138 is connected with 40 circuit 19 through either of the contacts associated therewith, the lamp illuminates phototube 158 and switch 8 is caused to open to disconnect valves 13 from circuit 6.

Although but a few embodiments of the present invention have been illustrated and described, it will be apparent to those skilled in the art that various changes and modifications may be made therein without departing from the spirit of the invention or from the scope of the appended 50 claims.

It is claimed and desired to secure by Letters Patent:

1. In an electric valve control system, the combination with a main electric current circuit, an 55 electric valve connected to said main circuit for controlling the flow of current therethrough, a source of electric current for said main circuit, a switch for connecting said source to said main circuit, an auxiliary electric current circuit insulated from said main circuit, and a second auxiliary electric current circuit connected to said main circuit comprising means for controlling the conductivity of said valve responsive to an abnormal operating condition of said valve for 60 rendering said valve non-conductive, of means connected to the first said auxiliary circuit and comprising a light sensitive device for controlling the operation of said switch, an electric light source arranged to illuminate said light sensitive 65 device, and means responsive to the occurrence of a plurality of operations of said conductivity controlling means within a predetermined period of time for controlling the supply of current to said light source to cause opening of said switch. 70

2. In an electric valve control system, the combination with an electric current circuit, an electric valve, means comprising a switch for effecting the connection of said circuit with said valve for the flow of current therethrough, of means for controlling said flow of current comprising an element of said valve, means for impressing a potential on said element to control the conductivity of said valve, means comprising a light sensitive device for varying the magnitude of said potential in such a sense as to regulate the said flow of current, means for causing operation of said light sensitive device, a second light sensi-

tive device, means operable responsive to an abnormal operating condition of said valve for varying said potential in such a sense as to render said valve non-conductive and for causing operation of the second said light sensitive device, and means operable responsive to the operation of the second said light sensitive device for causing operation of said switch to effect the disconnection of said valve from said circuit. 5
